TOY SWAMP CRAFT

George W. Ptaszek, Pascoag, R.I., assignor to
Hasbro Development Corp.

Filed Sept. 9, 1974, Ser. No. 504,657

Term of patent 3½ years

Int. Cl. D21—01

U.S. Cl. D34—15 AJ

FIG. 1

FIG. 2

FIG. 3

FIG. 4

FIG. 5

FIG. 6

FIG. 7

FIG. 1 is a perspective view of a toy swamp craft showing my new design;

FIG. 2 is a right-side elevational view thereof;

FIG. 3 is a left-side elevational view thereof;

FIG. 4 is a top plan view thereof;

FIG. 5 is a rear end view thereof;

FIG. 6 is a bottom plan view thereof; and

FIG. 7 is a front end view thereof.

I claim:

The ornamental design for a toy swamp craft, substantially as shown.
